UNITED STATES PATENT OFFICE.

AUGIE L. HANSEN, OF EVANSTON, ILLINOIS, ASSIGNOR TO JUSTRITE MANUFACTURING COMPANY, OF CHICAGO, ILLINOIS, A CORPORATION OF ILLINOIS.

ACETYLENE-LAMP.

1,233,663.

Specification of Letters Patent. Patented July 17, 1917.

Application filed August 28, 1916. Serial No. 117,128.

To all whom it may concern:

Be it known that I, AUGIE L. HANSEN, a citizen of the United States, and a resident of Evanston, in the county of Cook and State of Illinois, have invented certain new and useful Improvements in Acetylene Lamps, of which the following is a specification.

My invention relates to acetylene lamps and involves important features of construction and operation.

Mine lamps to which my invention refers usually comprise a water container and a carbid container with a water tube extending downwardly from the water container. In prior structures such water tube usually extends a considerable distance from the water container in order to bring its end well into the carbid when the carbid container is coupled to the water container. With this arrangement the end of the water tube must be crammed into the carbid when a freshly charged carbid container is applied and such cramming action may interfere with proper application of the carbid container in getting it properly centered in the receiving socket on the water container, this being particularly true where the coupling between the containers is in the form of threading. If the water tube does not extend entirely to the carbid there will be an over-abundance of water fed to the carbid before sufficient gas pressure will be generated to hold back the water.

In general the object of my invention is to overcome the above defects in prior structures. More in detail the object is to provide a water tube which will not extend into the carbid and which is provided with means for entrapping below its water outlet the gas generated as soon as the first water reaches the carbid, which gas exerts pressure at the water outlet to prevent excessive water flow immediately after opening of the water valve and before the carbid container becomes filled with gas under operating pressure. The gas entrapping means is movable along the tube and is shifted by the swelling slaking carbid to act as an agitator therefor.

On the accompanying sheet of drawings I have shown a lamp embodying the features of my invention. In this drawing—

Figure 1 is a vertical diametrical sectional view of the lamp body and carbid

container, the water tube being shown in full,

Fig. 2 is an enlarged sectional view of the lower end of the lamp body and the carbid container and water tube, 60

Fig. 3 is a view of the inside of the carbid container receiving socket, and

Fig. 4 is a top view of the carbid container.

The miner's cap lamp shown on the drawing comprises a water container 5 and the carbid container 6. One end of the water container is closed by a reflector 7 and the opposite end has a hook 8 and the clamp 9 for supporting the lamp on a cap. At the lower part of the water container is the cylindrical socket 10 for receiving the reduced neck 11 of the carbid container, the lower end of the socket flaring to form the flange 12 which is parallel with the beveled shoulder 13 of the carbid container, a washer 14 being inserted between the shoulder and flange to form a sealing fit when the containers are brought together. Any means may be provided for securing the containers together. As shown a shallow cup member 15 is secured to the top of the socket 10 and has the lower sections of its side walls deflected outwardly to form semi-circular helically extending ledges 16 and 17, and the upper edge of the carbid container neck is deflected inwardly and bent to form semi-circular helically extending flanges 18 and 19. When the carbid container is inserted in the socket and then turned the helical flanges and ledges will engage and will draw the carbid container into the socket to compress the washer 14 between the flange 12 and the shoulder 13. A tube 20 extends through the top of the socket 10 and the cup 15 and deflects laterally to extend axially through the reflector and seats a burner tip 21 at its outer end. To strain the gas passing from the carbid container into the tube 20 an annular strainer frame 100 22 of cup-shaped cross-section may be secured in the cup 15 to communicate at its open rear end with the tube, the gas being caused to pass through the small straining openings 23 before it can reach the tube. 105

Extending vertically through the water container and axially through the socket 10 is the water tube 24 which is contracted at its lower end to form a valve seat 25 surrounding the water outlet 26. In the tube 110

is the cylindrical valve stem 27 having the conical valve end 28 for coöperating with the seat 25, the stem at its upper end having the turning handle 29. The water tube 5 has also the spirally extending slot 30 into which a pin 31 extends from the valve stem, and from the upper end of the spiral slot the vertical slot 32 extends to the upper end of the water tube. With this arrangement 10 when the stem is turned while the pin is in the spiral slot the stem will be raised and lowered to open and close the valve outlet 26 and when the valve reaches the vertical slot 32 the stem may be withdrawn from the 15 water tube. Near the bottom of the water container the water tube has the water inlet 33. In order to retard the flow of water through the water tube to the outlet 26 the valve stem at its lower end has the spiral 20 groove 34 cut therein, this groove together with the water tube wall forming the long spiral water passageway or duct 35 through which the water must pass before it reaches the outlet 26.

25 In accordance with my invention I provide on the lower end of the water tube a tubular structure 36 forming a hood. This hood is shiftable on the water tube and when in its lowermost position is held on the tube 30 by the engagement of the inturned flange 37 at its upper end with the annular shoulder 38 at the bottom of the water tube. The water tube projects a comparatively 35 short distance into the carbid container so that the valve outlet 26 is above the normal level of carbid freshly charged into the carbid container, the container being usually filled half full. The hood 36, however, normally hangs from the lower end of the water 40 tube and when the carbid container is secured to the water container it will extend downwardly approximately to the normal carbid level and will rest on the carbid, as shown in Fig. 1. Now, when the water valve is 45 opened water will drop to the carbid directly below the hood and the first gas generated will flow upwardly into the hood and will exert pressure at the water outlet to prevent excessive water flow, and such control 50 will be maintained until the carbid container becomes filled with gas at operating pressure, which operating pressure will then prevent excess water flow. As the carbid becomes moistened it will slake and swell 55 and will exert upward pressure against the hood but the hood being free to slide on the water tube it will rise with the slaked carbid and then the slaked carbid between the hood and the solid carbid will act some- 60 what like blotting paper to prevent excessive water flow and also to distribute the moisture to the sides of the container so that more even consumption of the carbid takes place. The shifting hood will also 65 serve to agitate the slaked carbid so that

it cannot become too dense or hard. Preferably I also provide an extension 39 projecting through the valve outlet 26 from the lower end of the valve stem, this extension being shown in the form of a length 70 of flexible wire cable. By turning the valve stem the extension will agitate the slaked carbid. Should the pressure become excessive in the carbid container, gas can readily pass through the slaked carbid and through 75 the passageway 35 and water inlet 33 to the water container from whence it can pass to the exterior through the slot 32 or vent openings 40 in the plug 41 provided for the filling opening 42.

The lamp described is particularly adaptable for miners' use. There is nothing to prevent centering and securing of the carbid container to the water container. At the same time there can be no excessive flow of 85 water immediately after the water valve is opened for the hood at the lowered end of the water tube will entrap the first gas generated and this gas will regulate the lamp until the carbid container becomes filled 90 with gas and operating pressure. The water is evenly and uniformly distributed to the solid carbid and the accumulated slaked carbid can be agitated at any time to prevent clogging or to increase the water flow 95 and the size of the flame. The lamp will burn with the ordinary service size flame from the time the water valve is first opened until the carbid is exhausted practically without need of adjustment. 100

I do not of course desire to be limited to the exact construction and operation shown and described as changes and modifications may be possible which would still come within the scope of the invention. 105

I claim as follows:

1. In an acetylene lamp, the combination of a water container, a carbid container, a water outlet for the water container, and a hood carried by the water container below said outlet and extending to substantially the normal level of fresh carbid in the carbid container whereby the gas generated by the first flow of water will be entrapped below the outlet to exert pressure for controlling the flow of water to the carbid. 110

2. In an acetylene lamp, the combination of a water container, a carbid container, a water tube extending from the water container and terminating a distance above the 120 normal level of fresh carbid in the carbid container, and an extension tube suspended from and freely slidably on the water tube to bridge the space between the water tube end and the carbid when the lamp is started 125 and to be freely raised by the expanding carbid during slaking thereof.

3. In an acetylene lamp, the combination of a water container, a carbid container, a water tube extending from the water con- 130

tainer and terminating a distance above the normal level of fresh carbid in the carbid container, and an extension suspended from and freely slideable on said water tube to bridge the space between the end of the water tube and the carbid, said extension being closed on its sides but having its lower end wide open for the entrance of gas generated by the first flow of water, such gas being enclosed 5 below the water tube outlet to exert pressure for controlling the flow of water to the carbid.

4. In an acetylene lamp, the combination of a water container, a carbid container, a water tube extending from the water container and terminating a distance above the normal level of fresh carbid in the carbid container, and a tubular extension on said water tube for bridging the space between the lower end of the water tube and the car- 10

20

bid, said extension being entirely free to be raised by the expanding slaking carbid.

5. In an acetylene lamp, the combination of a water container having a receiving socket, a water tube extending from the water container into said receiving socket, a carbid container having a throat for engaging in said socket, said water tube terminating a distance above the normal level of fresh carbid in the carbid container when said container is secured in said socket, and an extension on said water tube freely slideable thereon to be raised by and maintained above the carbid during the inserting and securing movement of said carbid container 25 30 35 in said socket.

In witness whereof I hereunto subscribe my name this 25th day of August, A. D. 1916.

AUGIE L. HANSEN.
